George Spiess Inventor.

UNITED STATES PATENT OFFICE

GEORG SPIESS, OF LEIPZIG, GERMANY

PLATEN PRINTING PRESS

Application filed December 17, 1929, Serial No. 414,738, and in Switzerland July 19, 1929.

The invention relates to platen printing presses, and is concerned in particular with the grippers holding the sheets on the platen, its object being to obtain simple and reliable action of pneumatic grippers combined with facility and speed in placing and removing the sheets.

The invention is illustrated in the accompanying drawing, in which

10 Fig. 1 is a front elevation, and

Fig. 2 a side elevation of the relevant parts of a platen press.

15 Fig. 3 is a section on the line 3—3 of Fig. 1, and

Fig. 4 a section on the line 4—4 of Fig. 3.

Figs. 5 and 6 are sections, to a larger scale, of one of the sheet grippers, and

Fig. 7 is a section on the line 7—7 of Fig. 5.

20 Fig. 8 is an elevation showing another form of gripper.

Figs. 9 and 10 are respectively a front view and a side view of the top part of one of the grippers, and

Fig. 11 is a view similar to Fig. 10 but 25 showing a portion of the gripper in the collapsed state.

The platen 1 and the bed 2 are indicated only in part, by broken lines. The platen has at the bottom, near its face, two lateral eyes 3, in which is mounted a spindle 4, and on the spindle are mounted two brackets 5 carrying a broad bar 6, which has a channel 7 extending lengthwise thereof. In the floor of this channel there is an under-cut 30 groove 8, into which fit the coned heads of screw bolts 9, whereby approximately Z-shaped holders 10 for the sheet grippers, seated in the channel 7, are fixed to the bar 6. The grippers 11 fit into grooves in the 35 holders 10 and are fixed therein by means of retaining plates 12 clamped over them by means of screws 13.

The gripper 11 shown in Figs. 5 and 6 is a flattened tube, closed at the top, with an orifice 14 near the top, facing the platen, and having a rectangular bend at the bottom, to form an arm 15 for convenient connection to a flexible tube.

To the back of the bar 6 there is fixed a 40 tube 16 having two unions for connection to

flexible tubes. Each of these unions is fitted with a stop-cock 17, and the unions are connected by flexible tubes 18 to the grippers 11. The tube 16 also has a union 19 connected by a flexible tube 20 to the housing of a rotary valve 21 fixed to one side of the bed, and this valve housing is connected by a tube 22 to the suction side of an air pump or blower 23. The function of the valve is to open and close communication between the tubes 20 and 22 at intervals, and for this purpose there is on the spindle 24 of the valve a double armed abutment 25, with two rollers 26, 27, in the paths of abutments 28, 29 fixed to the platen. When the platen rocks to the 55 position shown in Fig. 2 the abutment 29, striking the roller 27, rotates the valve so that communication between the tubes 20 and 22 is interrupted, and when the platen rocks forward the abutment 28 strikes the roller 60 26, and the valve is opened.

The bar 6 has at the rear a small projection 30, with an eye in which there is a stud 31 forming a pivot for a rod 32. This rod has a longitudinal bore 33, with a coiled spring 34 therein, and a small plunger 35 attached to this spring. The stud 31 has an enlargement 36 at the part on which the hollow rod 32 is mounted, and inside the rod the part 36 has a recess 37, into which the plunger 35 65 80 is thrust by the spring when the recess faces the plunger. A pivot 38 connects to the rod 32 a rod 39, which at its opposite end is slid- 75 able in an eye 40 fixed to a pivot 41 in a bearing 42 on the bed. There is a collar 43 on the rod 39, preventing its withdrawal 85 from the eye 40, and between this eye 40 and a shoulder 44 on the rod there is a coiled spring 45.

The spring 34 in the hollow rod 32, thrusting the plunger 35 into the recess 37, tends to hold the bar 6 and rod 32 in such position relatively to each other that the rod 32 abuts against a boss 6^a projecting from the bar. The spring 45, acting on the rods 39 and 32 90 and bar 6, tends to press the grippers 11 against the face of the platen, but the collar 43 so limits the thrust of the rod 39 that when the platen rocks back, as shown in Fig. 2, it rocks away from the grippers. The grip- 95 100

pers can then be moved by hand in either direction. If they are thrust towards the platen face the bar 6 rocks away from the rod 32, and if they are thrust in the opposite direction the rod 39 is moved, compressing the spring 45.

When the platen rocks forwards for an impression, and the grippers are pressed against its face, the spring 45 is compressed.

10. Approximately at the time of impression the valve is opened to connect the tubes 20 and 22, so that when the platen swings back and ultimately swings clear of the grippers 11 the sheet 46 is retained by the grippers by suction, as shown in Fig. 2. At about the time when the platen has completed its rearward swing the attendant takes hold of the sheet, and the valve is closed by the abutment 29, so that the grippers release the sheet.

20. Each gripper 11 may with advantage be constructed of two parallel strips 47 of springy steel, spaced apart by wires, preferably piano wires, at the edges, as shown in Fig. 7, the wires being soldered, welded or otherwise joined to the steel strips.

The grippers are capable of sliding movement in their holders 10, in the direction of their length, for purposes of adjustment, the movement being limited in one direction by the arms 15 and in the other direction by abutments 49 on the grippers.

In the modification shown in Fig. 8 the gripper has a rectangular bend at the upper end, and the orifice 14 is in the horizontal part 50.

In the modification shown in Figs. 9 to 11 there is a rubber suction cup at the upper end of the gripper. A rubber sheath 51 fits over the top of the gripper, and to this is attached the cup 52, there being in the sheath, at the base of the cup, a hole 53 registering with the orifice of the gripper. The cup is compressed between the platen and the impression surface (Fig. 11), and its effort to expand again, when the platen swings back, creates a suctional effect assisting the suction due to the pump. The cup fully expands and releases the sheet when air is admitted to the gripper.

50. What I claim as my invention and desire to secure by Letters Patent of the United States is:—

1. In a platen printing press the combination of a platen, sheet grippers for holding a sheet on said platen, each gripper having an air channel therein and a suction orifice for holding the sheet, means pivotally connecting said grippers to said platen, means elastically pressing said grippers against the face of said platen when said platen rocks forwards for impression, and holding said grippers clear of said platen face when said platen has rocked rearwards, a suction conduit connected to the air channels in said grippers,

and valve mechanism actuated by said platen controlling said suction conduit.

2. In a platen printing press the combination of a platen, sheet grippers for holding a sheet on said platen, each gripper having an air channel therein and a suction orifice for holding the sheet, means pivotally connecting said grippers to said platen, means elastically pressing said grippers against the face of said platen when said platen rocks forwards for impression, and holding said grippers clear of said platen face when said platen has rocked rearwards, a suction conduit connected to the air channels in said grippers, and valve mechanism actuated by said platen controlling said suction conduit, the means holding said grippers clear of said platen face allowing said grippers to be forcibly rocked towards said face.

3. In a platen printing press the combination of a platen, sheet grippers for holding a sheet on said platen, each gripper having an air channel therein and a suction orifice for holding the sheet, and consisting of two elastic steel strips facing each other and two steel wires joined to said strips at the edges thereof, spacing said strips apart, means pivotally connecting said grippers to said platen, means elastically pressing said grippers against the face of said platen when said platen rocks forwards for impression, and holding said grippers clear of said platen face when said platen has rocked rearwards, a suction conduit connected to the air channels in said grippers, and valve mechanism actuated by said platen controlling said suction conduit.

4. In a platen printing press the combination of a platen, sheet grippers for holding a sheet on said platen, each gripper having an air channel therein and a suction orifice for holding the sheet, means pivotally connecting said grippers to said platen, said connecting means including holders wherein said grippers are adjustable, means elastically pressing said grippers against the face of said platen when said platen rocks forwards for impression, and holding said grippers clear of said platen face when said platen has rocked rearwards, a suction conduit connected to the air channels in said grippers, and valve mechanism actuated by said platen controlling said suction conduit.

5. In a platen printing press the combination of a platen, sheet grippers for holding a sheet on said platen, each gripper having an air channel therein and a suction orifice for holding the sheet, means pivotally connecting said grippers to said platen, said connecting means including a member whereon said grippers are adjustable transversely of the platen face, means elastically pressing said grippers against the face of said platen when said platen rocks forwards for impression, and holding said grippers clear of said platen

face when said platen has rocked rearwards, a suction conduit connected to the air channels in said grippers, and valve mechanism actuated by said platen controlling said suction conduit.

5 6. In a platen printing press the combination of a platen, sheet grippers for holding a sheet on said platen, each gripper having an air channel therein and a suction orifice for holding the sheet, and having an elastic suction cup at said orifice, means pivotally connecting said grippers to said platen, means elastically pressing said grippers against the face of said platen when said platen rocks forwards for impression, and holding said grippers clear of said platen face when said platen has rocked rearwards, a suction conduit connected to the air channels in said grippers, and valve mechanism actuated by said platen controlling said suction conduit.

10 7. In a platen printing press the combination of a platen, sheet grippers for holding a sheet on said platen, each gripper having an air channel therein and a suction orifice for holding the sheet, and having an elastic sheath and a suction cup joined to said sheath, said cup registering with said suction orifice, means pivotally connecting said grippers to said platen, means elastically pressing said grippers against the face of said platen when said platen rocks forwards for impression, and holding said grippers clear of said platen face when said platen has 15 rocked rearwards, a suction conduit connected to the air channels in said grippers, and valve mechanism actuated by said platen controlling said suction conduit.
